Patented Feb. 5, 1974

230,225

CONE CAP

Alberto Birlain Schafier, Amsterdam 218-201,
Mexico 11, D.F. Mexico

Filed Apr. 20, 1972, Ser. No. 246,119

Term of patent 14 years

Int. Cl. D2—03

U.S. Cl. D2—250

Fig. 1.

Fig. 2.

FIG. 1 is a front elevational view of a cone cap showing my new design;

FIG. 2 is a lateral elevational view from one side;

FIG. 3 is a lateral elevational view from the other side;

FIG. 4 is a rear elevational view; and

FIG. 5 is a top view.

I claim:

The ornamental design for a cone cap, as shown.
